UNITED STATES PATENT OFFICE.

GUY O. BAKER, OF ATLANTIC, IOWA.

UNLOADING DEVICE.

Application filed October 21, 1920. Serial No. 418,556.

To all whom it may concern:

Be it known that I, GUY O. BAKER, a citizen of the United States, and resident of Atlantic, in the county of Cass and State 5 of Iowa, have invented a certain new and useful Unloading Device, of which the following is a specification.

The object of my invention is to provide a device of simple, durable and inexpensive 10 construction, for quickly and efficiently unloading gravel and the like from gondola cars, which device may be easily and quickly placed in operative position relative to the said car.

15 A further object is to provide in a device for unloading gravel and the like from gondola cars, an improved derrick which is of light construction and may be quickly and easily placed in operative position.

20 A further object is to provide in an unloading device for gondola cars and the like, an improved delivery chute adapted to be quickly attached and detached, and also capable of being adjusted to meet the various 25 working conditions to which devices of this class are subjected, and further capable of being quickly and easily folded to permit wagons and the like to be moved to filling position.

30 Still a further object is to provide an unloading device employing a drag shovel or scoop, and improved means for hitching and handling said scoop.

35 My invention consists in the construction, arrangement and combination of the various parts of the device, whereby the objects contemplated are attained, as hereinafter more fully set forth, pointed out in my claims, and illustrated in the accompanying drawings, 40 in which:

Figure 1 is a transverse sectional view of a portion of a gondola car showing my improved loading device attached in side elevation.

45 Figure 2 is a detail sectional view, showing segments of the derrick.

Figure 3 is a side elevation of a portion of a gondola car showing my improved unloading device in elevation, a portion of the 50 car being broken away to show the manner in which the scoop is operated.

Figure 4 is a plan elevation of the scoop, showing my improved method of hitching.

Figure 5 is a side elevation of same; and

Figure 6 is a detail view showing the brace 55 member for my improved delivery chute.

In the drawings I have shown my device attached to the body portion of a gondola car 10, although it may be used in other ways.

The device comprises an A-shaped frame member 11, having a horizontal bar 12 and a plate 13. The plate 13 is riveted to the members 11 near the apex of the frame, and the bar 12 is riveted at a point near the lower 60 end of the members 11. The lower end of each of the members 11 is provided with a clamp 14, having a set screw 15. Each set screw 15 is provided with a head 16 having an opening 17, which is for the purpose of 65 receiving a bar by which the set screw may be rotated. The clamps 14 are designed to be placed over the upper edge of the car body 10, and when so placed the A-frame 70 member 11 will rest in a perpendicular position.

For supporting the upper end of the frame 75 11 against lateral movement, I have provided a brace member having a wing 19 at its upper end, which is designed to rest on top of the plate 20, the said plate being secured to the upper ends of the members 11, as illustrated in Figure 3. The wing 19 is secured in position by means of a pin 21. The lower end of the member 18 has a clamp 22 80 similar to the clamp 14, with the exception that it is secured by means of a single bolt 23. This bolt provides a pivotal movement between the clamp and the bar 18. The bar 18 is provided with a series 85 of openings 24, by means of which the clamp 22 may be adjusted so that the bar 18 may be adapted to fit cars of different widths. The clamp 22 is provided with a set screw similar to the set screw 15, and is designed to be secured to the upper edge of the car 10 on 90 the opposite side from which the member 11 is secured.

95 By this arrangement it will be seen that I have provided a derrick of simple construction and of light weight, which may be easily attached to the car body and placed in position.

100 Pivotedly secured to the member 18, near its top end, is what I shall term a hitch bar 105 25, which is provided with a series of openings 26. The free end of this hitch bar is designed to be passed through an opening 27 in the plate 13.

This hitch bar 25 is designed to carry one end of a cable 28, which is detachably connected thereto by means of a hook 29 and a pulley 30 having a hook member 31. The cable 28 is provided with a movable block 32, and has its free end extended through the pulley, which is hitched in the bar 25 near the plate 13, then extended downwardly to a pulley 33 which may be staked to the ground or tied to the rail on which the car is mounted. The free end of the cable is provided with a singletree 34, to which a draft animal may be hitched.

The pulley 32 is designed to carry a scoop 36, which is hitched thereto by means of chain members 36 and 37. The chain members 36 are hitched near the forward end of the scoop and to a ring 38. The chain 37 has one end hitched to the loop 38, while the other is designed to be attached to the rear end of the scoop by means of a hook 39. This hook 39 and chain 37 provide means whereby the angle of the scoop 35 may be varied relative to the angle of the cable 28 when in an operative position. The scoop 35 is provided with handles 40, which are secured to the back thereof by means of straps 41 extending beneath the bottom at each side of the scoop, and terminating at a point where the chains 36 are attached. A transverse member 42 is provided on the under side of the scoop 35, and has each end terminating with the pivot of the chains 36. Thus it will be seen that I have provided a very rigid scoop, with reinforcing members at the points where the greatest strain is applied to the scoop. By this arrangement it will be seen that the body member may be made of very light material without sacrificing the strength of the scoop.

For delivering the material, I have provided a chute 43 having diverging side members 44. This scoop is designed to be placed adjacent to the outside of the car in an inclined position, and is attached to the member 12 of the frame 11 by means of hinged hook members 45. Each of the hook members 45 is designed to be placed in a slot 46 in the member 12, thus providing means for easily and quickly detaching the chute member.

For supporting the outer end of the chute I have provided horizontal brace members 47, which are formed tubular and designed to telescopically receive a U-shaped member 48, the member 48 being secured in position by means of set screws 49. The braces 47 are secured to the chute 43 by means of pivots 50 mounted in the bracket members 51.

When the chute 43 is placed in position the member 48 is designed to rest against the side of the car, with the members 47 in a horizontal position. The angle of the chute may be varied by adjusting the mem-

ber 48 in the members 47, while the side member 48 is held against downward movement by means of chains 52, each of which is adjustably connected to the upper ends of the side members of the chute by means of hooks 53.

It often happens in driving a wagon into position beneath the delivery end of the chute, that it is necessary to drop the chute out of the way, and this may be easily and quickly done by merely elevating the free end of the member 48. This will permit the free end of the chute to swing downwardly and rest in a substantially vertical position, as shown by dotted lines in Figure 1. When the wagon is in position the chute may be quickly moved into position by dropping the member 48.

As the angle of the chute is varied by adjusting the members 47 and 48, the length of the chain 52 will also have to be adjusted in order to keep the said members in a horizontal position. This is easily and quickly done, as before described, by means of the hooks 53.

The practical operation of the device is as follows: Assuming that the cable 28 has been hooked to the bar 25, and the pulley 30 placed in position near the plate 31, and that the movable block 32 and the scraper 35 are in position, and that the scoop is in the position shown in dotted lines in Figure 1, the operator will grasp the handles 40 and draw the scoop backward or outward to the opposite side of the car, after which the chain 37 is adjusted on the hook 39 to give the scoop the proper angle. The draft animal is then started and the scoop drawn radially toward a point beneath the bar 25. After the scoop has reached the said point, a further movement of the draft animal will cause the scoop to be elevated vertically, and if the angle of the chain 37 has been properly adjusted the scoop 35 will assume a position as indicated by dotted lines. After the scoop is in the said position, the draft animal is allowed to back up slightly, while the operator elevates the handles 40, causing the forward end of the scoop to be tilted downwardly and into the chute 43. The scoop is then ready to be returned to filling position.

In operating this device, however, it should be noted that the operator should commence at the far side or corners and draw the material inwardly radially to a point below the bar 25. By this method the opposite sides and each end of the car will be excavated first, which will provide an incline from which the shovel may be filled. This is clearly illustrated in both Figures 1 and 3. As the angle of the incline varies, the length of the chain 37 will have to be slightly adjusted to meet the requirements of the different angles.

Another important feature in operating

this device is to get the scoop in the right position for easily discharging into the chute. This is accomplished by the proper placing of the cable 28 on the pulley 30 on the hitch bar 25.

Sometimes it is desired to fill a car, rather than empty it, in which case the hook 29 of the cable 28 may be placed in one of the openings in the extreme end of the hitch bar 25, while the pulley 30 may be placed on the opposite side of the plate 13 from that shown in Figure 1.

One important thing in a device of this kind is to be able to easily and quickly attach the device to the car. It has been demonstrated by actual practice that a large car may be entirely emptied of material in sixty minutes. For that reason it is very essential that the derrick be taken down and placed in position in a very short length of time, as otherwise the time for setting up the device would be greater than the time required to empty the car.

In this connection it will be seen that the chute may be easily detached by simply lifting it upwardly, which will cause the hooks 45 to disengage the member 12, the members 47 and 48 folding against the bottom of the chute. The derrick may be quickly removed by simply releasing the three set screws and removing the pin 29.

I claim as my invention:

1. In a device of the class described, the combination of a container, an A-shaped frame detachably mounted vertically at one side of the container, a brace bar detachably secured to the apex or said A-frame on the opposite side of said container, a hitch bar, having a series of hitch openings, near the apex of said frame member, an outwardly extending chute detachably hooked to said A-frame, means for adjusting the angle of said chute, and means for folding the said chute to substantially a vertical position adjacent to the outside of said container.

2. In a device of the class described, the combination of a container, an A-shaped frame detachably mounted vertically at one side of the container, a brace bar detachably secured to the apex of said A-frame on the opposite side of said container, a hitch bar, having a series of hitch openings, near the apex of said frame, an outwardly extending chute detachably hooked to said A-frame, means for adjusting the angle of said chute, means for folding the said chute to substantially a vertical position adjacent to the outside of said container, a scoop, a block and cable attached to said hitch bar and said scoop for moving the scoop from a filling position to a position to deliver to said chute, and means on said scoop for adjusting its angle relative to said cable.

3. In a device of the class described, the combination of a container, a supporting frame supported vertically above one side of said container, adjustable means for detaching said supporting frame, a brace bar secured to the upper end of said supporting frame extending across the container and having its lower end supported on the opposite side of said container, means for detachably securing said brace bar to the last said side member of said container, means for adjustably connecting the detachable means with said brace bar, a scoop, flexible scoop actuating means, and means for attaching the flexible means to said brace and said frame member.

4. In a device of the class described, the combination of a container, a supporting frame supported vertically above one side of said container, adjustable means for detaching said supporting frame, a brace bar secured to the upper end of said supporting frame extending across the container and having its lower end supported on the opposite side of said container, means for detachably securing said brace bar to the last said side member of said container, means for adjustably connecting the detachable means with said brace bar, a scoop, flexible scoop actuating means, means for attaching the flexible means to said brace and said frame member, an outwardly extending chute detachably secured to the lower end of said supporting frame, means for adjusting the angle of said chute, and means for pulling said chute to substantially a vertical position adjacent to the outside of the container.

5. In a device of the class described, the combination of a container, an A-shaped frame detachably mounted vertically at one side of the container, a brace bar detachably secured to the apex of said A-shaped frame and to the opposite side of said container, a clamp device for securing the lower end of said brace bar to said container, and means for adjustably connecting said brace bar and said clamp together.

6. In a device of the class described, the combination of a container, an A-shaped frame detachably mounted vertically at one side of the container, a brace bar detachably secured to the apex of said A-shaped frame and to the opposite side of said container, a clamp device for securing the lower end of said brace bar to said container, means for adjustably connecting said brace bar and said clamp together, a scoop, a flexible means for operating said scoop, and means for operatively attaching said flexible means to the apex portion of said frame.

Des Moines, Iowa, September 30, 1920.

GUY O. BAKER.
